CLAIM

The ornamental design for footwear upper, as shown and described.

DESCRIPTION

FIG. 1 is a perspective view of the footwear upper embodying the new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIGS. 1-7 show features of an article of footwear in phantom lines. These features are shown for environmental purposes and do not form any part of the claimed design. Further, the phantom lines immediately adjacent the solid-line portions of the design form the boundary of the design, with the phantom lines forming no part of the claimed design. FIG. 7 illustrates a removable portion of the article of footwear spaced from and oriented relative to the remainder of the footwear.

The spacing and orientation of the removable portion (when removed) shown in FIG. 7 is for clarity of disclosure only, and forms no part of the claimed design.
